ELECTRON DISCHARGE DEVICE CONTROL SYSTEM

Isadore K. Dortort, Milwaukee, Wis., assignor to Allis-Chalmers Manufacturing Company, Milwaukee, Wis., a corporation of Delaware

Application February 5, 1934, Serial No. 709,820

21 Claims. (Cl. 175—363)

This invention relates in general to improvements in electron discharge device control systems and more particularly to means for energizing the control electrodes of an electric valve to control the flow of current therethrough in a more accurate and efficient manner than was possible heretofore.

Electric valves are frequently utilized for controlling the flow of current through circuits associated therewith to thereby constitute systems such as alternating current rectifying, direct current inverting, frequency changing and other systems. In general, the flow of current through each anode of the valve is to be released periodically by suitable means such as control electrodes, the flow of current being prevented by maintaining the control electrode at a potential below the so-called critical potential which is approximately the same as the potential of the cathode, and is released by bringing the control electrode to a potential higher than the critical potential or cathode potential. In valves of the vapor type, the value of the critical potential depends on the operating conditions within the valve so that, when the control electrode potential varies in a gradual manner, the release of the flow of current occurs at intervals which are not accurately defined. It is, therefore, desirable to impress, on the control electrode, a potential suddenly passing from a finite negative value to a finite positive value to thereby release the flow of current at precise intervals even when the critical potential does not remain constant. Conversely, if a control electrode is used of the type whereby the flow of current may be suddenly interrupted by deionization of the arc path, the control electrode potential should preferably pass suddenly from a positive value to a negative value. In valves of the vacuum type, the impedance of the valve varies with the potential of the control electrode and it is then advantageous to vary such potential suddenly between a negative value sufficient to prevent the flow of current and a positive value sufficient to cause the valve to oppose a minimum impedance to the flow of current therethrough and thus obtain such flow of current at the highest possible efficiency. Control potentials having such characteristics may be conveniently obtained by means of circuits supplied with alternating current and supplying current to inductive devices through controllable auxiliary electric valves. The connections between the auxiliary circuits and the control electrodes may be made in several different ways as will appear herein-
55 after.

It is, therefore, among the objects of the present invention to provide a control system for an electron discharge device in which the control electrodes of the device are energized through circuits comprising auxiliary electron discharge devices.

Another object of the present invention is to provide a control system for an electron discharge device in which the control electrodes of the device receive potentials of which the polarity is suddenly reversed at recurring intervals.

Another object of the present invention is to provide a control system for an electron discharge device in which the control electrodes of the device receive potentials from circuits containing inductive devices and which are controlled by means of auxiliary electron discharge devices.

Another object of the present invention is to provide a control system for an electron discharge device in which the control electrodes of the device receive potentials which are regulated in relation with operative conditions of the system.

Another object of the present invention is to provide a control system for an electron discharge device in which the control electrodes of the device receive potentials including a negative potential impressed thereon upon occurrence of a disturbance in the system.

Objects and advantages, other than those above described, will be apparent from the following description when read in connection with the accompanying drawings, in which:

Fig. 1 diagrammatically illustrates one embodiment of the present invention applied to the control of an electric valve utilized in a system for rectifying alternating current and in which the control potentials are regulated in relation with the power output of the valve;

Fig. 2 is a diagram of the wave form of some of the voltages appearing in the circuits of the embodiment illustrated in Fig. 1;

Fig. 3 diagrammatically illustrates a portion of a modified embodiment of the present invention differing from the embodiment illustrated in Fig. 1 in that the control potentials are regulated in relation with only the flow of current through the valve;

Fig. 4 diagrammatically illustrates another modified embodiment of the present invention differing from the embodiment illustrated in Fig. 1 in the method of connection of the control electrodes of the valve with the energizing circuits therefor and in which the control potentials are

regulated in function of operating conditions of the supply line;

Fig. 5 is a diagram of the wave form of some of the voltages appearing in the circuits of the embodiment illustrated in Fig. 4;

Fig. 6 diagrammatically illustrates a portion of a modified embodiment of the regulating circuits utilized in the embodiment illustrated in Fig. 4 for regulating the control potentials in relation 10 with the power factor of the flow of current in the supply line;

Fig. 7 diagrammatically illustrates a further modified embodiment of the present invention differing from the previously illustrated embodiments in that the control electrodes of the valve receive potentials having a frequency double the frequency of the potentials impressed on the associated anodes, such potentials being regulated in relation with the intensity of the flow of current 20 rent through the valve;

Fig. 8 is a diagram of the wave form of some of the potentials appearing in the circuits of the embodiment illustrated in Fig. 7;

Fig. 9 diagrammatically illustrates the application 25 of the control electrode energizing circuits illustrated in Fig. 7 to the control of an electric valve regulating the flow of current through the windings of an electric motor and in which the control potentials are regulated in relation with the speed of such motor;

Fig. 10 diagrammatically illustrates a modification 30 of the speed responsive elements of the embodiment illustrated in Fig. 9; and

Fig. 11 diagrammatically illustrates a portion 35 of the regulating circuits differing from the circuits illustrated in Fig. 9 in that the control potentials are regulated thereby in function of the power output of the motor.

Referring more particularly to the drawings by 40 characters of reference, reference numeral 16 designates an alternating current supply line herein represented as a three-phase line operating at any suitable voltage having any suitable frequency. It is assumed that it is desired to 45 convert alternating current from line 16 into direct current to be supplied to a direct current line having a negative conductor 17 and a positive conductor 18. Line 16 is accordingly connected with the primary winding 21 of a transformer 19 having a secondary winding 22 arranged in any suitable manner and provided for example with a plurality of phase displaced portions connected in star to form a neutral point connected with conductor 17. The different 50 phase portions of winding 22 are severally connected with the anodes such as 23 of an electric valve 24 of any suitable type. The preferred form of valve illustrated in the present and following embodiments is the type in which the current 55 is conducted through mercury vapor produced at a cathode 26 connected with conductor 18. It will be understood that valve 24 is provided with the usual discharge ignition and maintaining means which are well known and therefore not shown. As is usual the potential of the cathode 26 will be taken as datum for the potentials impressed on the discharge control means consisting of control electrodes such as 27, such potentials then being equal to the electromotive forces of any circuits connected 60 between such control electrodes and the cathode. In a similar manner the cathodes of any auxiliary valves utilized in the present invention will be taken as datum for the potentials impressed 65 on the associated control electrodes.

The control electrodes of the valve receive periodic potentials from the system to be described immediately hereafter. Such system comprises a transformer 28 energized from line 16 and having a secondary winding delivering voltages 70 similar to the voltages of line 16 and of winding 22. Such secondary winding comprises a plurality of phase displaced portions connected in star in the embodiment illustrated in Fig. 1 and severally supplying current to a plurality of independently functioning control circuits each comprising a resistor as at 29 in series with a reactor as at 31 and an auxiliary electric valve as at 32. The auxiliary valves are of any suitable type but it is preferred to utilize valves of the type in which the discharge is conducted through a gas or vapor and of which the action is controlled by means of a control electrode as at 30.

The control electrodes of the auxiliary valves are severally connected with the secondary winding 34 of a transformer 33 energized from line 16 to receive therefrom phase displaced alternating potential components superimposed on a common unidirectional potential component appearing in a circuit connecting the neutral point of winding 34 with the cathodes of the auxiliary valves. Each reactor 31 is connected in parallel with the primary winding of a transformer as at 36 having a secondary winding connected between conductor 18 and one of the control electrodes as at 27 of the main valve; if so desired transformer 36 may be omitted and replaced by a secondary winding arranged on the core of reactor 31. It will be understood that a source of constant uni-directional potential such as a battery 37 may be inserted in the common connection of the main control electrodes with conductor 18 although such battery will be considered as being omitted in describing the operation of the system. It will also be understood 40 that the circuits of the control electrodes of the main and auxiliary valves may comprise suitable impedance means for limiting the flow of current therethrough as is usual in the art.

The connection between the neutral point of 45 winding 34 and the cathodes of the auxiliary valves may comprise a source of either constant or variable uni-directional potential, such potential varying in relation with the power output of valve 24 in the present embodiment. To obtain 50 such variation a current transformer 38 is inserted in one of the connections between winding 21 and line 16, such current transformer having a secondary winding provided with a midtap and supplying current to a resistor 39. Such 55 secondary winding is also connected with the anodes of a pair of auxiliary valves 41 which are preferably of the high vacuum type in which the flow of current is continuously regulated in function of the anode and control electrode potentials. 60 The cathodes of valves 41 and also of the set of valves such as 32 are connected with a tap of a voltage divider 42 connected across lines 17, 18, and the control electrodes of valves 41 are jointly 65 connected with conductor 18 through a suitable bias battery 40 and the resistor 42. The midtap of the secondary winding of current transformer 38 is connected with the neutral point of winding 34. To obtain a substantially uniform potential between the neutral point of winding 34 and the cathode of the auxiliary valves, suitable filtering means may be provided such as a reactor 43 and capacitors 44 as is well known in the art.

The operation of the system will be more clearly understood by reference to Fig. 2 in which 75

curve 46 represents the voltage impressed on anode 23 as a result of energization of transformer 19 from line 16. Assuming that the flow of current through valve 24 has not yet been established, current transformer 38 receives no appreciable amount of current and the neutral point of winding 34 is accordingly at the potential of the cathodes of valves 41 and 32. The connections of transformer 28 with line 16 and with the 5 auxiliary valves are such that the anodes of the valves 32 receives therefrom a potential which may be represented by curve 47 which is similar to curve 46 and is in suitable phase relation therewith. Control electrode 33 then receives, from 10 winding 34, an alternating potential which is preferably in phase coincidence with the potential of the associated anode and may, therefore, be represented by curve 49 becoming positive at an instant represented by point A of the time 15 abscissa. Valve 32 accordingly becomes conductive at time A and carries current during the time interval A, B of positive energization of the anode and during a further interval BD as a result of the presence of reactor 31 in the circuit 20 thereof. Resistor 29 and reactor 31 are so proportioned as to cause reactor 31 to absorb the greater part of the voltage impressed on the circuit thereof; the voltage drop across reactor 31 25 then follows substantially curve AFBEDC, such potential suddenly decreasing to zero at time D at which the current tends to reverse but such reversal is prevented by the valve action of valve 32. A voltage of similar wave shape is impressed 30 on control electrode 27 by transformer 36, such voltage becoming positive while anode 23 is positive and releasing the flow of current through such anode. Such flow of current continues until anode 23 becomes negatively energized from 35 winding 22 or when the flow of current is released through another anode at higher potential. Such sequence of operation is repeated for 40 each anode of valve 24 to cause the flow therethrough of a substantially uniform current.

As a result of such flow of current, current 45 transformer 38 impresses on resistor 39 and on the anodes of valve 41 potentials proportional to the intensity of such current and therefore also proportional to the intensity of the flow of current through valve 24 and line 17, 18. Such potentials cause a flow of uni-directional current 50 through valves 41, such flow of current being modified by the action of the control electrodes of such valves which are energized from voltage divider 42 at a positive potential in relation with 55 the magnitude of the voltage of line 17, 18. The uni-directional output voltage of valves 41 impressed between the neutral point of winding 34 and the cathodes of the valves such as 32 therefore varies in relation with the intensity of the 60 flow of current through line 17, 18 times the voltage of such line, and therefore in relation with the power output of the valve 24. Such voltage may be represented by a straight line 48 intersecting curve 49 at a time G at which 65 control electrode 30 becomes positive to release the flow of current through valve 32. Such flow of current continues during interval GB and continues during a further interval BH which is, however, shorter than interval BD. If the voltage 70 drop in the discharge through valve 32 is considered as negligible, the voltage appearing at the terminals of reactor 31 will follow the dis-symmetrical heavy line curve derived from curve 47. Such voltage is impressed on transformer 36 75 of which the secondary voltage is then represent-

ed by curve 51 which is identical to the heavy line curve above mentioned but which is displaced with respect to the axis of abscissas by an amount such that the average value of such voltage over a complete cycle be zero, as a uni-directional component of voltage cannot be transmitted through a transformer. It will be noted that at time G the voltage represented by curve 51 suddenly passes from a negative value to a positive value, thereby causing a positive release of the 10 flow of current through anode 23 at time G irrespectively of the operating conditions within the valve 24. Such sequence of operation is repeated successively for every anode and control electrode of valve 24 to cause the output voltage of valve 15 24 to follow curve 52 comprising portions of the several voltage curves of the anodes of the valve. If so desired, the voltage impressed on line 17, 18 20 may be rendered substantially uniform by providing suitable filtering means in the circuits as is well known in the art. If the load of line 17, 18 increases the potential impressed by current transformer 38 and valves 41 on the neutral point of winding 34 increases to an extent commensurate with such increase of load, causing 25 the auxiliary valves such as 32 to become conductive at a later instant of the voltage cycle thereof, whereby the control potential impressed on the control electrodes of the valve 24 become positive at a later instant and the average 30 output voltage of valve 24 decreases. If the load of line 17, 18 decreases, the output voltage of valve 24 is caused to increase by the opposite process. The system accordingly causes the flow 35 of energy through transformer 19 and valve 24 to be maintained at a substantially uniform value, although it will be understood that the circuits may also be adjusted to regulate such flow of energy only when such flow exceeds a predetermined value to cause such flow of energy 40 to be limited in its magnitude, and to be unregulated when it remains below the limiting value.

In the present system, therefore, transformer 45 19 and the valve 24 constitute electric translation means connected with supply line 16 and comprising an alternating current winding 22 and also an electric valve 24 having anodes 23, control electrodes 27 and a cathode 26. Line 16 impresses an electromotive force similar to an electromotive force of winding 22 on a control 50 circuit comprising resistor 29, reactor 31 and auxiliary valve 32 to thereby generate a periodic potential impressed on a load circuit constituted by the connection of control electrode 27 with cathode 26. Transformer 36 impresses, on such 55 load circuit, a potential component similar to a component of the potential across a portion of the control circuit, such portion being reactor 31. Valve 32 controls the flow of current through the circuit in such a manner as to impress on 60 control electrode 27, potentials of signs and magnitudes operative to control the flow of current through valve 24. Valve 32 is provided with discharge controlling means such as control electrode 30 cyclically controlling the operation of the valve as a result of the connection thereof with energizing means operating in relation with the voltage cycle of line 16. Such energizing means impress, on control electrode 30, potentials 65 of signs and magnitudes operative to cause valve 32 to be alternately conductive and non-conductive at recurring intervals in relation with voltage cycle of line 16 and winding 22. For regulating the action of such energizing means, the 70 75

control potentials comprise a uni-directional component in relation with the magnitude of a component of the flow of current in line 16 and also in relation with the magnitude of the flow of energy between line 16 and line 17, 18. Such component results from an alternating potential in relation with the intensity of the flow of current through valve 24 obtained from current transformer 38 and rectified and regulated by valves 41.

In the embodiment illustrated in Fig. 3, the alternating potential impressed by current transformer 38 on winding 34 through valves 41 is regulated through the valve in response to the intensity of only the flow of current through valve 24. To obtain such result, the control electrodes of valves 41 receive a direct current potential in relation with the intensity of the flow of current through conductor 17 from a shunt 53 inserted therein, the average output voltage of valves 41 then varying in relation with the square of the current through valve 24 as the currents flowing through current transformer 38 and through shunt 53 are both in direct proportion with such current. When such flow of current increases, the average output voltage of valve 24 is accordingly caused to decrease and conversely when the flow of current decreases, the output voltage of valve 24 increases with the result that the flow of current is regulated at a substantially uniform value. The circuits may, however, also be adjusted to limit the flow of current to a predetermined value and to leave such flow of current unregulated when such value is not reached thereby. It will be understood that the action of shunt 53 on valves 41 may be magnified by insertion of suitable voltage amplifying means in the connections therebetween or by providing valves 41 with screen grids as is well known in the art.

In the embodiment illustrated in Fig. 4 the connections of the several windings of transformer 28 are assumed to be such as to cause the potentials represented by curves 47 and 46 to be in the phase relation as illustrated in the diagram of Fig. 5. In the present embodiment, each transformer as at 36 is connected between the anode and the cathode of the associated valve to impress on the associated control electrode as at 27 potentials opposite in sign to those appearing across the valve. The direct current voltage component impressed on each control electrode as at 30 through winding 34 is made to vary in relation with the component of the flow of current through line 16 which is not utilized for energizing line 17, 18. Assuming that line 16 is supplied from a single generator 66, a potential in relation with such current component may be obtained by means of a current transformer 67 inserted in line 16 between the connection of transformer 19 therewith and the outgoing portion of the line. The secondary winding of current transformer 67 is utilized for impressing a uni-directional potential between the cathodes of the auxiliary valves as at 32 and the neutral point of winding 34 in a manner similar to that illustrated in Fig. 1, the control electrodes of valves 41 receiving, however, alternating potentials obtained from a potential transformer 68 connected with line 16 through a suitable impedance device 69' to obtain the desired phase relation between the anode and control electrode potentials of valves 41. In the present embodiment, the cathodes of all valves are connected with conductor 18. The connec-

tions of the control electrodes of valve 24 includes a resistor 69 connected between cathode 26 and battery 37. Such resistor is connected to receive current from one or more current transformers 71 inserted in the connection between winding 21 and line 16, such current being rectified by means of a rectifier device 74 to thereby cause the appearance of a substantially uniform negative voltage across the terminals of resistor 69. Each current transformer 71 is bridged by a circuit comprising a reactor 72 and a capacitor 73 constituting a non-linearly resonant element having a low reactance while the flow of current through the associated current transformer 71 is less than a predetermined permissible value and having a high reactance when such flow of current exceeds the permissible value.

If the voltage drop of the discharge within valve 32 be again neglected it will be seen that the voltage between the anode and the cathode of valve 32 and impressed on the primary winding of transformer 36 may be represented by the portions of curve 47 not drawn in heavy line in Fig. 2, such portions being drawn in heavy line in Fig. 5. The voltage appearing across the terminals of the secondary winding of transformer 36 then follows a curve 76 which is similar to the heavy line curve above mentioned reversed in polarity and drawn with respect to an axis of abscissas so chosen that the average voltage over a complete cycle is zero. The voltage represented by curve 76 passes suddenly from a negative to a positive value to release the flow of current through anode 23 in a positive and accurate manner, the flow of current occurring similarly through the several anodes to cause the output voltage of valve 24 to again follow curve 52. In the present embodiment, if the average output voltage of valves 41 represented by line 48 increases, the release of the flow of current through valve 32 is again retarded but the instant at which such flow of current ceases occurs at an earlier time. The flow of current through anode 23 is therefore released at an earlier instant and the average output voltage of valve 24 is increased. Conversely, when the average voltage of valves 41 decreases, the average output voltage of valve 24 decreases to maintain such output voltage in predetermined relation with the current through transformer 67 and the voltage impressed on transformer 68.

During normal operation of valve 24 the flow of current remains below a predetermined value in relation with the rated value of the valve and reactor 72 and capacitors 73 are then in resonance for the frequency of the voltage impressed thereon by current transformer 71, such frequency being that of the voltage in line 16. Each current transformer 71 is therefore substantially short circuited by the reactor and capacitor connected therewith so that the potential impressed thereby on resistor 69 is at a negligible value. Upon occurrence of a disturbance causing the flow of current through transformer 19 to reach an excessive value, one or more of the current transformers 71 impress, on the associated reactor 72 and capacitor 73, an alternating voltage of such magnitude as to cause the reactance of the reactor to vary and thereby to cause the reactor and the capacitor to be no longer in resonance. The potential of the secondary winding of the current transformer is therefore impressed at substantially the full value thereof on resistor 69 through rectifiers 74 to cause a negative potential to be

impressed across resistor 69 on the control electrodes of valve 24 of such magnitude as to cause the flow of current through valve 24 to cease.

In the present embodiment therefore transformer 36 connects the load circuit, comprised by the control electrode 27 and cathode 26, across valve 32 to impress on control electrode 27 a potential component similar to a component of the potential between the anode and the cathode of valve 32. The energizing means for control electrode 30 are regulated by the action of the uni-directional potential of valves 41 which is in relation with the magnitude of a component of the flow of current in line 16 and also in relation with the power factor of such flow of current due to the control of valves 41 by means of transformer 68. Current transformers 71 constitute means for obtaining an alternating potential in relation with the intensity of the flow of current through transformer 19 and valve 24, rectifiers 74 converting such potential into uni-directional control potential impressed on control electrode 27 by means of resistor 69. Reactor 72 and capacitor 73 constitute non-linearly resonant impedance means controlling the relation between such uni-directional potential and the intensity of the flow of current through valve 24.

In the embodiment illustrated in Fig. 6, the anodes of valves 41 are energized from transformer 68 whereas the control electrodes of the valves are energized from transformer 67. In general the voltages of line 16 may be assumed to be of constant value so that the average output voltage of valves 41 will be equal to a substantially constant value modified by the action of the control electrodes in accordance with the power factor of the current flowing through current transformer 67. The output voltage of valve 24 will accordingly be regulated to vary in relation with such factor to cause the power factor of the total current supplied by generator 66 to be regulated in the desired manner.

In the embodiment illustrated in Fig. 7 the secondary winding portions of transformer 28 are connected to form three single phase windings having separate neutral points. Each winding thus formed is connected with the anodes of a pair of valves as at 32 and 77 whereby each reactor as at 31 and each resistor as 29 receives substantially uniform rectified current, the reactors and resistors then being equal in number to one-half of the number of valves. Transformer 36 is then again connected across reactor 31 to supply control potential to control electrodes 27 and 78 associated with anodes 23 and 79 receiving potentials in phase opposition from winding 22. In the present embodiment the uni-directional potential impressed between the cathodes of the valves and the neutral point of winding 34 is made to vary in relation with the intensity of the flow of current through transformer 19, such potential being obtained from current transformer 38 in a manner similar to that illustrated in Fig. 3 or by rectifying the secondary voltage of transformer 38 by means of a bridge rectifier 80 and impressing the rectified voltage on the voltage divider 83. The relation between the uni-directional potential thus obtained and the intensity of the flow of current through transformer 19 is controlled by means of a reactor 81 and a capacitor 82 constituting a non-linearly resonant element having a high impedance when the flow of current through transformer 19 is below the value desired therefor and a low impedance when such flow of current is greater than the value de-

sired therefor, such impedance varying rapidly when the current departs from the desired value by a small amount. The cathodes of the valves 32, 71, etc., are normally connected with transformer 28 through the reactors as at 31 and 5 through contacts of a relay 84 energized from a current transformer 86 inserted in the connection between transformer 19 and line 16. Such relay is so adjusted as to operate upon flow of excessive current through transformer 19 to then 10 connect each reactor with the associated control electrodes of valve 24 instead of with the cathodes of the associated auxiliary valves.

In the diagram of Fig. 8 the potential impressed on the anode of valve 77 is represented by curve 86 similar to curve 47 but displaced therefrom by 180°. The potential of control electrode 85 of valve 77 may then be represented by curve 87 displaced with respect to curve 49 by 180° indicating that control electrode 85 becomes positive at a time represented by point L to thereby release the flow of current through valve 77. The combined output voltage of valves 32 and 77 may be derived from curves 47 and 86 as shown in the heavy line drawn in Fig. 8, such voltage being 20 impressed, to its greatest extent, on reactor 31, the reactance of which is assumed to be sufficient to cause the flow of uni-directional current therethrough to be uninterrupted. Control electrodes 27 and 78 will then receive a common potential 30 represented by curve 88 similar to the heavy line curve above mentioned but displaced with respect to the axis of abscissas so as to render the average voltage thereof over a complete cycle equal to zero. Such energization of the control electrodes causes the flow of current through anode 23 to be released at time G as in the embodiment illustrated in Fig. 1 and the flow of current through anode 79 to be released at time L at a voltage represented by curve 89. The flow 40 of current through the remaining pairs of anodes of valve 24 is released in a similar manner to cause the flow of current to occur therethrough at a voltage represented by curve 52.

From a consideration of Fig. 8 it appears that 45 during interval KL anode 79 becomes increasingly positive with respect to cathode 26, the voltages of the anode and cathode being represented by curve 89 and a curve substantially identical with curve 52 respectively. During such interval anode 50 79 has an increasing tendency to carry current which must be overcome by the action of the control electrode 78 until the flow of current is released at time L. During interval KL control electrode 78 becomes increasingly negative, the 55 potential thereof being represented by curve 88 and therefore effectively opposes the tendency of anode 79 to carry current prematurely with the use of a potential of minimum amplitude.

When the flow of current through transformer 60 19 increases or decreases, the output voltage of current transformer 38 and rectifier 80 increases or decreases to a greater extent controlled by reactor 81 and capacitor 82 to cause the output voltage of valve 24 to decrease or to increase and 65 thus maintain the flow of current through valve 24 at substantially a predetermined value or to limit such flow of current to the desired value. Upon occurrence of a disturbance causing the flow of excessive current through current transformer 36, relay 84 energized thereby is caused to operate to disconnect the several reactors from the cathodes of the valves and to connect each reactor with the associated control electrodes. As a result of such operation control electrodes 27 75

and 78 receive, from valves 32 and 77, a negative potential through a circuit including control electrodes 23 and 78, a contact of relay 84, reactor 31, resistor 29, transformer 28, valves 32 and 77, to conductor 18. Flow of current also occurs from conductor 18 through battery 37, transformer 36, a contact of relay 34, reactor 31, resistor 29, transformer 28 and valves 32 and 77, the flow of such current through reactor 31 causing the uni-directional potential impressed on the control electrodes by the valves to be maintained at a substantially uniform value operative to cause the flow of current through the associated anodes to cease. The remaining control electrodes of valves 24 being similarly energized, the flow of current through the valve ceases and the normal operation can be resumed.

Line 16, accordingly, operates as a source of current for the pair of valves 32 and 77 which are operatively connected to supply uni-directional current therefrom to reactor 31 and co-operates with current transformer 38, rectifier 80 and transformer 33 to impress, on the control electrodes of the valves, recurring potentials of signs and magnitudes operative to cause each of such valves to be alternately conductive and non-conductive in sequence (with respect to the other valve) in relation with the voltage cycle of line 16. Such control potentials include a uni-directional potential component in relation with the intensity with the flow of current through transformer 19 and valve 24, the relation between such potential and the intensity of such current being controlled by the non-linearly resonant impedance means 81 and 82. Relay 34 operates in response to abnormal conditions in the system for connecting the valves 32 and 77 with control electrodes 23 and 78 to constantly impress negative potential thereon.

In the embodiment illustrated in Fig. 9, line 16 supplies current to the windings of a motor 93 through a single phase transformer 92 having a secondary winding provided with a midtap, the flow of such current being controlled by an electric valve 91 similar to valve 24 but provided with anodes different in number from the number of anodes of valve 24. Line 17, 18 is connected between the midtap of transformer 92 and the cathode of valve 91 to supply current through the field winding 94 of the motor. The armature windings 96 of the motor are severally connected between transformer 92 and the anodes such as 23 and 78 of valve 91. The control electrodes such as 27 and 78 of the valve are generally maintained negative by means of a suitable source such as a pair of rectifying devices 97 converting current received from line 16. The flow of current through the particular armature windings 96, operative to cause a torque to be impressed on the shaft of the motor, is controlled by means of a distributor 98 having a brush operating in relation with the movement of shaft 95 of the motor and supplying, to the control electrodes, control potentials obtained from valves 32 and 77 in a manner similar to that illustrated in Fig. 7. The anodes of valves 32 and 77 are connected with a transformer 99 and control electrodes 30 and 85 are connected with a transformer 101, such transformers being energized from line 16. The uni-directional potential component impressed on control electrodes 30 and 85 is supplied from a direct current generator 102 driven from shaft 95 and therefore delivering current at a voltage in relation with the speed of the motor.

In the position shown the distributor is without effect on the action of the control electrodes of valve 91 with the exception of control electrodes 27 and 78 and the flow of current through all anodes except anodes 23 and 79 is therefore precluded as a result of the negative energization of the associated control electrodes. Control electrodes 27 and 78 receive, through distributor 98, a periodic potential to permit the alternate flow of current through anodes 23 and 79. Such currents combine in valve 91 to cause the flow of substantially uniform direct current through conductor 18, field winding 94, conductor 17 back to transformer 92, causing a torque to be impressed on the shaft of the motor resulting in rotation of said shaft in a predetermined direction. After a material length of time which may amount to several cycles of the voltage of line 16, the brush of the distributor 98 engages with another segment of the distributor, thereby causing the flow of current through anodes 23 and 79 to cease and causing the flow of current to be released through another pair of anodes. Such sequence of operation is repeated for every pair of anodes and armature windings to cause the flow of substantially uniform current through the motor and the continued rotation of the shaft in a uniform direction. If the speed of the motor increases, the output voltage of generator 102 increases, causing valves 32 and 77 to carry current at a later portion of the voltage cycle of line 16 and thereby causing the average output voltage impressed on windings 96 and valve 91 to decrease. Conversely, when the speed of the motor decreases, the output voltage of valve 91 increases to thereby maintain the speed of the motor at a substantially uniform value. Such value may be regulated by means of a rheostat 105 inserted in the field circuit of generator 102. Such generator therefore constitutes means for obtaining a uni-directional potential component in relation with the speed of the motor and which component is to be impressed on control electrodes 30 and 85 of the auxiliary valves.

In the modified embodiment partially illustrated in Fig. 10, alternating current generator 103 is substituted for generator 102, the output voltage of generator 103 being converted into a uni-directional voltage component by means of a bridge rectifier 104. For a particular adjustment of rheostat 105, the output voltage of generator 103 is proportional to the speed of the motor and the uni-directional voltage obtained therefrom controls the operation of the motor in the same manner as was done by means of generator 102 in the embodiment illustrated in Fig. 9. The relation between such voltage and the speed of the motor may be varied by means of rheostat 105 and also by insertion across the terminals of generator 103 of a capacitor 107 and of a reactor 106 across which rectifier 104 is connected. The reactor and the capacitor constitute an impedance element which becomes resonant for a particular value of the frequency of the voltage of generator 103 and therefore for a particular speed of the motor. When the speed of the motor approaches such value, the voltage across reactor 106 increases rapidly, thereby causing the output voltage of valve 91 to decrease and to maintain the speed of the motor at the substantially uniform value. Such value may be adjusted by adjusting the capacities of capacitor 107. When the speed of the motor varies, the magnitude of the voltage of generator 103 as well as the frequency thereof

varies and such frequency value may be sufficient to cause variation of the resonant frequency of reactor 106 with capacitor 107, and the variations of the magnitude of such voltage may therefore be utilized instead of the variations of the frequency for controlling the speed of the motor.

In the embodiment illustrated in Fig. 11, the field winding of generator 102 is excited in function of the flow of current through transformer 82 by means of a current transformer 101 and a bridge rectifier 104. The output voltage of generator 102 then becomes proportional to the speed of the motor as a result of the operation of the armature thereof from shaft 35 and also proportional to the intensity of the flow of current through the motor which in turn is proportional to the torque of the motor. Such voltage is therefore proportional to the torque times the speed of the motor or to the output energy of the motor and maintains such energy at a substantially uniform value.

Although but a few embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. The combination with an alternating current supply circuit, an electric current work circuit, and electric valve means interconnecting said circuits comprising an anode and a cathode constituting spaced electrodes for the flow of current therebetween, of means for controlling said flow of current comprising a control electrode constituting an element of said valve means, and means for producing and impressing on said control electrode potential impulses of substantially perpendicular wave front comprising a control circuit having included therein a reactor and an auxiliary electric valve connected to receive an electromotive force similar to the electromotive of said supply circuit, discharge controlling means connected for cyclically controlling the operation of said auxiliary valve to thereby control the flow of current through said reactor, and means coupling said reactor with said control electrode to impress on the latter a potential component similar to a component of the potential across said reactor.

2. The combination with an alternating current supply circuit, an electric current load circuit, and electric valve means interconnecting said circuits comprising an anode and a cathode constituting spaced electrodes for the flow of current therebetween, of means for controlling said flow of current comprising a control electrode constituting an element of said valve means, and means for producing and impressing on said control electrode potential impulses of substantially perpendicular wave front comprising a control circuit having included therein a reactor and an auxiliary electric valve connected to receive an electromotive similar to the electromotive of said supply circuit, discharge controlling means for said auxiliary valve, energizing means operating in relation to the voltage cycle of said supply circuit for controlling the action of said discharge controlling means, and means coupling said reactor with said control electrode to impress on the latter a potential component similar to a component of the potential across said reactor.

70 3. In a system of the character described, the combination with a load circuit, of means for producing and impressing on said circuit potential impulses of substantially perpendicular wave front comprising a source of alternating current, a reactor, means comprising an electric valve having an anode and a cathode connecting said source with said reactor and constituting spaced electrodes for the flow of current of unidirection only through said reactor, means for rendering said valve conductive and non-conductive at recurring intervals in relation with the voltage cycle of said source of current, and means connecting said load circuit across said reactor.

4. In a system of the character described, the combination with a load circuit, of means for producing and impressing on said circuit potential impulses of substantially perpendicular wave front comprising a source of alternating current, a reactor, means comprising an electric valve having an anode and a cathode connecting said source with said reactor and constituting spaced electrodes for the flow of current of unidirection only through said reactor, means for rendering said valve conductive and non-conductive for said flow of current at recurring intervals in relation with the voltage cycle of said source of current, and means comprising a transformer inductively connecting said load circuit across said reactor.

5. In a system of the character described, the combination with a load circuit, of means for producing and impressing on said circuit potential impulses of substantially perpendicular wave front comprising a reactor, means comprising a plurality of electric valves each comprising an anode and a cathode connecting said source with said reactor and constituting spaced electrodes for the flow of current of unidirection only through said reactor, means comprising a plurality of control electrodes severally associated with said anodes and a source of control potential for sequentially rendering said valve conductive and non-conductive for said flow of current at recurring intervals with respect to the voltage of said source of current, and means for connecting said load circuit across said reactor.

6. In a system for controlling the flow of electric current, an electric current supply line, electric translation means connected with said line and comprising an alternating current winding and an electric valve having an anode, a control electrode and a cathode; an electric current output line connected with said translation means, a circuit connected to receive an electromotive force similar to an electromotive force of said winding, and including a reactor and an auxiliary electric valve having an anode, a control electrode, and a cathode; means for impressing on the second said control electrode potentials of signs and magnitudes operative to cause the second said valve to be alternately conductive and non-conductive at recurring intervals in relation with the voltage cycle of said winding, and a transformer connected to impress between the first said control electrode and cathode a potential component similar to a component of the potential between the second said anode and cathode.

7. In a system for controlling the flow of electric current, an electric current supply line, electric translation means connected with said line and comprising an alternating current winding and an electric valve having an anode, a control electrode and a cathode; an electric current out-

75

- put line connected with said translation means, a circuit connected to receive an electromotive force similar to an electromotive force of said winding, and including a reactor and an auxiliary electric valve having an anode, a control electrode, and a cathode; means for impressing on the second said control electrode potentials of signs and magnitudes operative to cause the second said valve to be alternately conductive and non-conductive at recurring intervals in relation with the voltage cycle of said winding, and means for impressing between the first said control electrode and cathode a potential component similar to a component of the potential drop in said reactor.
8. In a system for controlling the flow of electric current, an electric current supply line, electric translation means connected with said line and comprising an alternating current winding and an electric valve having an anode, a control electrode and a cathode, and an electric current output line connected with said translation means; a circuit connected to receive an electromotive force similar to an electromotive force of said winding, and including a reactor and a pair of auxiliary electric valves operatively connected to supply uni-directional current to said reactor, each valve having an anode, a control electrode, and a cathode; means for impressing on the second said control electrodes recurring potentials of signs and magnitudes operative to cause each of the second said valves to be alternately conductive and non-conductive in sequence with respect to the other valve in relation with the voltage cycle of said source, and means for impressing between the first said control electrode and cathode a potential component similar to a component of the potential drop in said reactor.
40. In a system for controlling the flow of electric current, an electric current supply circuit, electric translation means connected with said circuit and comprising an alternating current winding and an electric valve having an anode, a control electrode and a cathode; an electric current output circuit connected with said translation means, means including an auxiliary electric valve for impressing on said control electrode recurring potentials of signs and magnitudes operative to control the flow of current through the first said valve, said auxiliary valve having an anode, a control electrode and a cathode, and means for impressing control potentials on the second said control electrode and including means for obtaining an alternating potential in relation with the intensity of the flow of current through said translation means; and means for converting the last said potential into uni-directional control potential.
60. In a system for controlling the flow of electric current, an electric current supply circuit, electric translation means connected with said circuit and comprising an alternating current winding and an electric valve having an anode, a control electrode and a cathode; an electric current output circuit connected with said translation means, means including an auxiliary electric valve for impressing on said control electrode recurring potentials of signs and magnitudes operative to control the flow of current through the first said valve, said auxiliary valve having an anode, a control electrode and a cathode, means for impressing control potentials on the second said control electrode and including means for obtaining an alternating potential in relation with the intensity of the flow of current through said translation means; and means for converting the last said potential into uni-directional control potential.
70. In a system for controlling the flow of electric current, an electric current supply circuit, electric translation means connected with said circuit and comprising an alternating current winding and an electric valve having an anode, a control electrode and a cathode; an electric current output circuit connected with said translation means, means including an auxiliary electric valve having connections with the said control electrode for recurringly impress-
- through said translation means, non-linearly resonant impedance means controlling the relation between the last said potential and the intensity of said flow of current, and means for converting the last said potential into uni-directional control potential.
11. In a system for controlling the flow of electric current, an electric current supply circuit, electric translation means connected with said circuit and comprising an alternating current winding and an electric valve having an anode, a control electrode and a cathode, an electric current output circuit connected with said translation means; means including an auxiliary electric valve for impressing on said control electrode recurring potentials of signs and magnitudes operative to control the flow of current through the first said valve, said auxiliary valve having an anode, a control electrode and a cathode; and means for impressing control potentials on the second said control electrode and including means for obtaining a uni-directional potential in relation with the magnitude of the flow of energy between said circuits.
12. In a system for controlling the flow of electric current, an electric current supply circuit, electric translation means connected with said circuit and comprising an alternating current winding and an electric valve having an anode, a control electrode and cathode; an electric current output circuit connected with said translation means, one of said circuits being an alternating current circuit, means including an auxiliary electric valve for impressing on said control electrode recurring potentials of signs and magnitudes operative to control the flow of current through the first said valve, said auxiliary valve having an anode, a control electrode and a cathode; means for impressing control potentials on the second said control electrode and including means for obtaining an alternating potential in relation with the magnitude of a component of the flow of current in said alternating current circuit, and means for converting the last said potential into uni-directional control potential.
13. In a system for controlling the flow of electric current, an electric current supply circuit, electric translation means connected with said circuit and comprising an alternating current winding and an electric valve having an anode, a control electrode and a cathode; an electric current output circuit connected with said translation means, one of said circuits being an alternating current circuit, means including an auxiliary electric valve for impressing on said control electrode recurring potentials of signs and magnitudes operative to control the flow of current through the first said valve, said auxiliary valve having an anode, a control electrode and a cathode; and means for impressing control potentials on the second said control electrode and including means for obtaining a uni-directional control potential in relation with the power factor of the flow of current in said alternating current circuit.
14. In a system for controlling the flow of electric current, an electric current supply circuit, electric translation means connected with said circuit and comprising an alternating current winding and an electric valve having an anode, a control electrode and a cathode; an electric current output circuit connected with said translation means, means including an auxiliary electric valve having connections with the said control electrode for recurringly impress-

- ing thereon potentials of signs and magnitudes operative to control the flow of current through the first said valve, said auxiliary valve having an anode, a control electrode and a cathode; 5 means for impressing control potentials on the second said control electrode, and means responsive to abnormal conditions within the system for modifying the said connections of the second said valve to constantly impress a negative 10 potential on the first said control electrode.
15. In a system for controlling the flow of electric current, an electric current supply circuit, electric translation means connected with said circuit and comprising an alternating current winding and an electric valve having an anode, a control electrode and a cathode; an electric current output circuit connected with said translation means, means including an auxiliary electric valve for impressing on said control electrode recurring potentials of signs and magnitudes operative to control the flow of current through the first said valve, said auxiliary valve having an anode, a control electrode and a cathode; means for impressing control potentials 20 on the second said control electrode, means for obtaining an alternating potential in relation with the intensity of the flow of current through said translation means, non-linearly resonant impedance means controlling the relation between the last said potential and the intensity of said flow of current, means for converting the last said potential into uni-directional control potential, and means for impressing said uni-directional potential on the first said control electrode. 25
30. 16. In a system for controlling the flow of electric current, an electric current supply circuit, electric translation means connected with said circuit and comprising an alternating current winding and an electric valve having a plurality of anodes with associated control electrodes and a cathode; a load device connected with the first said winding and with said valve, means including auxiliary electric valves for impressing on said control electrodes recurring potentials of signs and magnitudes operative to control the flow of current through the first said valve, each said auxiliary valve having an anode, a control electrode and a cathode; and means for impressing control potentials on each second said 35 control electrode including means operable to produce an alternating potential variable in magnitude in dependence upon the intensity of the flow of current through said translation means and including means for converting the last said potential into uni-directional control potential. 40
45. 17. In a system for controlling the flow of electric current, the combination with an electric current supply circuit, an electric current load circuit, and electric valve means comprising an anode and a cathode interconnecting said circuits and constituting spaced electrodes for the flow of current therebetween, of means for controlling said flow of current comprising an element of said valve means, means comprising an auxiliary electric valve coupled with said element for recurringly impressing thereon potential of such sign and magnitude and during such moments as to control the moments of initiation of said flow of current, means for controlling the said moments of the impression of said potential on said element comprising an element of said auxiliary electric valve, means for impressing potential on the last said element of such sign and magnitude and during such moments as to 50
- 55 render the said auxiliary valve recurringly conductive, and means responsive to an abnormal condition of said system for rendering the said auxiliary valve constantly non-conductive. 5
18. In a system for controlling the flow of electric current, the combination with an electric current supply circuit, an electric current load circuit, and electric valve means comprising an anode and a cathode interconnecting said circuits and constituting spaced electrodes for the flow of current therebetween, of means for controlling said flow of current comprising an element of said auxiliary electric valve coupled with said element for recurringly impressing thereon potential of such sign and magnitude and during such moments as to control the moments of initiation of said flow of current, means for controlling said moments of impression of said potential on said element comprising an element of said auxiliary electric valve, means for impressing potential on the last said element of such sign and magnitude and during such moments as to render said auxiliary valve recurringly conductive, means operable responsive to an operating condition of said system for varying the moments of impression of said potential on the last said element, and means responsive to an abnormal condition of said system for impressing potential on the last said element of such sign and magnitude as to render the said auxiliary electric valve constantly non-conductive. 10
20. 19. The combination with an alternating current supply circuit, an electric current work circuit, and electric valve means interconnecting said circuits comprising an anode and a cathode constituting spaced electrodes for the flow of current therebetween, of means for controlling said flow of current comprising a control electrode constituting an element of said valve means, means for producing potential impulses of substantially perpendicular wave front comprising a control circuit having included therein a resistor serially connected with an inductive reactor and an auxiliary electric valve, discharge controlling means connected for cyclically controlling the initiation of said potential impulses, and means coupling said control circuit with said control electrode to impress on the latter a potential component similar to a component of the potential across a portion only of said control circuit. 25
30. 20. The combination with an alternating current supply circuit, an electric current load circuit, and electric valve means interconnecting said circuits and comprising an anode and a cathode constituting spaced electrodes for the flow of current therebetween, of means for controlling said flow of current comprising an element of said valve means other than said electrodes, means for impressing on said element a potential comprising an alternating voltage component and a unidirectional voltage component, and means operable in dependence upon variations in the said flow of current for varying the magnitudes of said components. 35
35. 21. In an electric current converting system, the combination with an electric current supply circuit, an electric current load circuit, and electric valve means interconnecting said circuits and comprising an anode and a cathode constituting spaced electrodes for the flow of current therebetween, of means for controlling said flow of current comprising an element of said valve means, means comprising an auxiliary electric 40
